[57] CLAIM

The ornamental design for a quick release latch for a bus seat or the like, as shown and described.

DESCRIPTION

FIG. 1 is a perspective view of a quick release latch for a bus seat or the like showing our new design;

FIG. 2 is a front elevational view thereof, the broken-line disclosure being for illustrative purposes only and forming no part of the claimed design;

FIG. 3 is a rear elevational view thereof;

FIG. 4 is a right side elevational view thereof, the left side being a mirror image of that shown;

FIG. 5 is a top plan view thereof; and,

FIG. 6 is a bottom plan view thereof.
